CUTTING DEVICES

Desmond Walter Molins, Deptford, London, England, assignor to Molins Machine Company Limited, London, England, a British company

Application November 30, 1953, Serial No. 395,069

Claims priority, application Great Britain
December 15, 1952

1 Claim. (Cl. 51—247)

This invention concerns improvements in or relating to rotary cut-off mechanisms of the kind used in cigarette-making machines.

In a cut-off mechanism for a cigarette-making machine the cutting blade is usually thin so as to enable the cigarette-rod to be cut cleanly. Some rigidity can be imparted to the blade by clamping it between rigid members, but part of the blade near the edge must be left free in order to enable it to pass through the cigarette-rod and through the ledger plate which supports the rod. This free part of the blade, due to its thinness, flexes easily. An example of such a device, called hereafter "a rotary cutting device of the kind referred to" is disclosed in United States Patent No. 1,860,197. In that example the blade is of the well-known sickle shape and the invention described later is for use with such blades.

Usually the blade is arranged to pass across a sharpening element once in each revolution of the cut-off mechanism so as to keep the blade constantly sharp. Difficulty is sometimes experienced in sharpening the blade satisfactorily, however, because if the sharpening element is advanced in an endeavour to grind more material from the blade edge, the increased pressure of the element against the blade causes the latter to bend away, due to its flexibility, so that the edge does not come into proper grinding contact with the sharpening element. In an extreme case the blade may be bent to such an extent that its side, rather than its edge, engages the sharpening element.

This difficulty does not often arise when the cut-off device operates on an ordinary cigarette-rod which consists wholly of tobacco enclosed in a paper wrapper. When harder or tougher materials than tobacco have to be cut, however, the knife is more rapidly blunted and requires greater pressure to resharpen it. For example when mouthpiece cigarettes are being made, the rod to be cut consists of double-length tobacco portions and double-length mouthpiece portions alternately, each of which has to be severed to produce individual mouth-piece cigarettes. The mouthpiece portions are often made of crepe paper or other material which is harder or tougher than tobacco and which blunts the edge of the cutting blade more than does a rod consisting of wrapped tobacco only. Similarly when mouthpiece portions are made, for example in the manner disclosed in United States Reissue Patent No. 20,138 by forming a continuous rod of mouthpiece material and cutting this rod into desired lengths in the same way as cigarettes are cut from a cigarette-rod, the cutting blade tends to be blunted, due to the tough nature of the material which it is required to cut more than it would be by an ordinary cigarette-rod.

According to the present invention there is provided a rotary cutting device of the kind referred to having a sickle-shaped flexible blade adapted to engage a sharpening element, during rotation of the device and comprising a support member which lies against the blade near the edge thereof when the blade engages the sharpening element,

2

to support the blade against bending by the said sharpening element.

The support member may be rotatable with the blade and as cigarette and like rods are always in practice supported by a ledger, usually a tube through which the rod passes, means may be provided for moving the support member relatively to the blade so that the support can be moved away from the cutting portion of the blade to avoid the ledger at the cutting position. For his purpose 5 the member may be pivotally supported on a carrier to which the knife is attached and a cam may be suitably arranged to cause the support member to move at the appropriate times.

In the case of the first specification mentioned above 15 the blade is carried on an arm or bar pivotally connected to two shafts having axes of rotation inclined to one another. One shaft gives rotation to the arm or carrier while the other gives the blade the motion of translation necessary when moving rods are cut. In this case the 20 support member is pivoted on the arm or carrier which is rotated by the first shaft and the cam is fixed so that its constructional centre is coaxial with the second shaft.

One construction according to the invention will be described with reference to the accompanying drawings 25 in which:

Figure 1 is a perspective view of the cutting device.

Figure 2 is a side elevation of the cutting device shown in Figure 1.

Figure 3 is a view of Figure 2 looking in the direction 30 of the arrow A but showing only the parts more pertinent to the present invention and drawn to a larger scale.

Referring first to Figure 1, this shows a perspective view 35 of a cut-off of the kind shown in the specification first mentioned. In the drawing, 1 is the sickle-shaped blade which is shown hatched for clearness and is held by a clamp 2 to a carrier 3. The carrier is pivoted to a shaft 4 which constitutes the driving shaft of the cut-off and a fork, parts of which are indicated at 6 is also pivoted to the carrier and joined to another shaft which is not 40 visible in the drawing. This other shaft is inclined at an angle to the shaft 4. As the shaft 4 rotates, the knife 1 is carried round and passing through a slot in a ledger 7 cuts through the rod which is supported by the ledger tubes. As will be understood from a study of United 45 States Patent No. 1,860,197 the combined effects of the two shafts and the fork 6 which constitutes part of a universal joint causes the blade to make complete rotations and at the same time to be translated substantially parallel to the axis of the shaft 4. This translational movement is to cause the knife to move at the same speed as the rod during the time it is actually cutting through the rod.

A grinding disc 8 is mounted as shown and driven 55 from the left-hand side by means not shown in the drawing and is so arranged that the blade 1 sweeps over it during every revolution and is thus kept sharp. As will be apparent from the foregoing description the blade 1 is liable to bend away from the grinder owing to its flexibility and to overcome this there is provided a curved plate 9, one side of which is in contact with the blade 1 at or near its cutting edge on the side opposite that which engages the grinder and supports the blade against bending. As shown in Figure 3 the curvature of the plate 9 is such that it is substantially parallel with the blade 60 edge. This support plate is pivoted at 10 and to its pivot is attached a cam lever 11 having a cam follower 15 at its free end which is not visible in Figure 1 of the drawing but which runs in a cam groove 12 formed in a plate 13. This plate is fixed to the housing of the 65 second shaft so that when the angle of this shaft is altered to increase or decrease the amount of translation, the cam is moved with it. The shape of the cam track is 70

such that as the plate 9 approaches the ledger it is caused to rotate on its pivot 10 so that its rear end moves inward from the edge of the knife and in this way the plate passes by the ledger without contacting it.

Referring now to Figures 2 and 3 of the drawings, it will be seen that the cam 13 is fixed to a fixed arm 14 by which the grinding wheel 8 is supported. The above mentioned cam follower is shown in Figures 2 and 3 and marked 15 while the second shaft which carries the fork 6 is marked 16. The angular disposition of this shaft and thus the blade translational movement is altered by shifting the shaft housing 5 in a curved block of a support bracket 17.

What I claim as my invention and desire to secure by Letters Patent is:

In a cutting device for severing an axially moving rod into lengths, a sickle-shaped cutting blade, a rotatable shaft, a carrier for said blade, said carrier and blade being supported on said shaft for rotation therewith and for simple swinging movement about an axis transverse to the rotational axis of said shaft, a second shaft rotatable about an axis inclined to the rotational axis of said first shaft, said second shaft having a portion thereof in engagement with said carrier, whereby a movement combining rotation and axial translation with respect to said first shaft is imparted to said blade, a sharpening device for said blade positioned to engage the blade during rotation of said carrier, a support member lying against the blade near the free edge thereof when the

blade engages the sharpening element, said support member being shaped to a curvature similar to that of the blade edge and lying substantially parallel to the said edge, whereby the blade is supported against bending by the pressure between it and the sharpening element, a pivotal mounting for said support member on the blade carrier, a fixed cam, a cam follower engaging said cam and operatively connected to said support member to displace the latter on its pivotal mounting toward and away from the edge of the blade, the cam having a contour such that the support member is held substantially parallel to the blade edge when the latter engages the sharpening element and is displaced on its pivotal mounting farther away from the free edge of the blade when the blade is passing through the axially moving rod.
